UNITED STATES PATENT OFFICE

120,138

DESIGN FOR A SUPPORT FOR A DRINK MIXER

Stephen J. Poplawski, Racine, Wis.

Application January 10, 1940, Serial No. 89,378

Term of patent 14 years

To all whom it may concern:

Be it known that I, Stephen J. Poplawski, a citizen of the United States, residing at Racine, in the county of Racine and State of Wisconsin, have invented a new, original, and ornamental Design for a Support for a Drink Mixer, of which the following is a specification, reference being had to the accompanying drawing, forming part thereof.

I claim:

The ornamental design for a support for a drink mixer, as shown.

STEPHEN J. POPLAWSKI.
